UNITED STATES PATENT OFFICE.

EZRA HOLDEN, OF CHICAGO, ILLINOIS.

TOY.

SPECIFICATION forming part of Letters Patent No. 276,586, dated May 1, 1883.

Application filed October 21, 1882. (Model.)

To all whom it may concern:

Be it known that I, EZRA HOLDEN, of Chicago, in the county of Cook and State of Illinois, have invented a certain novel device to be applied to the pictures of faces or busts of toys having faces, by which the eyes may be represented as winking or the tongue thrust from the mouth, as an amusement for children at Christmas time, by representing Santa Claus as winking, or thrusting his tongue out of his mouth, and being apparently alive, of which the following is a specification.

Figure 1 represents a front view of a pasteboard picture having holes $o o$ cut in it where the eyes should be and a slot for the mouth. Fig. 2 represents a back view of the same, but having connected with it a back piece, (marked a), and held in place by strips (marked $b b$) underneath which its upper and lower ends pass, said strips $b b$ being attached at their ends to the rear of the pasteboard picture. Fig. 3 represents a front view similar to Fig. 1, but having the eyes in their proper position.

On the front of the back piece, a , are painted or drawn eyes, which, when in place, fill the openings $o o$. There may also be attached to the front of the back piece, a , in proper place a strip of paper or other material painted red, in shape of and to represent a tongue, to be thrust through the slot for the mouth, as hereinafter described. There is also attached to this back piece, a , and also to the upper strip b , an elastic or spring, c , and there are projections to the back piece, a , confining it in its movements between the strips $b b$, so that when the elastic or spring is not drawn the painted eyes will fill the openings $o o$ and the tongue be out of sight. Attached to the bottom of the back piece, a , is a string, on pulling which downward until the lower projections reach the lower strip b the painted eyes are drawn down out of sight, appearing as if closed by winking, and by the same move-

ment, the strip d in Fig. 4, representing the tongue, is thrust forward through the slot for the lips or mouth. On loosening the string the back piece, a , is drawn up by the elastic or spring until stopped by the upper projection reaching the upper strip b , at which point the painted eyes are in proper place to fill the openings $o o$, and the tongue is withdrawn.

Fig. 4 represents the back piece, a , drawn down until the painted eyes are out of sight, and the tongue d is thrust through the opening for the mouth.

Fig. 5 represents two back pieces, $a a$, upon one of which a strip to represent a tongue is attached. With this arrangement a string would be attached to each piece $a a$, so that by pulling one or both strings either one or both eyes may be represented as winking, and the tongue may be operated or not, as desired.

With this picture thus prepared and attached to the wall of a room, or among the branches of a Christmas-tree, and the string attached to the lower end of the back piece, a , passing down behind a table or chair, the string may be carried along the floor or wall to a distant part of the room, and a person addressing the picture or asking questions of it responses would seem to be given by causing it to seem to wink or thrust its tongue out by the pulling of one or two strings.

What I claim as my invention, and desire to secure by Letters Patent, is—

75

1. The combination of the back piece, a , with the card-board B , and strips $b b$, substantially as set forth.
2. The combination of the elastic c , attached to the back piece, a , with the card-board B or with upper strip, b , substantially as described, and for the purpose set forth.

EZRA HOLDEN.
